UNITED STATES PATENT OFFICE.

CHARLES H. WEISKOPF, OF HAWTHORNE, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL PRECIPITATION OF SUSPENDED MATERIAL FROM GASES.

Application filed July 30, 1923. Serial No. 654,790.

This invention relates to an apparatus for separation of suspended material from gases and vapors by the action of an electrical field and the main object of the invention 5 is to provide apparatus of this character which will be especially adapted for use in the precipitation of material which tends to form a sticky or adherent deposit on the electrodes which cannot be readily removed 10 by the usual expedient of shaking or jarring the electrodes.

A further object of the invention is to provide an electrical precipitator of such construction that the electrodes thereof can 15 be readily removed and reinserted for the purposes of inspection and cleaning.

Another object of the invention is to provide an electrical precipitating apparatus which is especially adapted for treatment of 20 combustible gases liable to involve explosions within the apparatus.

The accompanying drawings illustrate an electrical precipitator embodying my invention, and referring thereto:

25 Fig. 1 is a horizontal section of the precipitator.

Fig. 2 is a vertical longitudinal section of the treater.

30 Fig. 3 is a vertical transverse section on line 3—3 in Fig. 2.

Fig. 4 and Fig. 5 are enlarged partial transverse and longitudinal sections showing the mounting of the precipitator electrodes and the removable closure means therefor.

35 My invention is herein illustrated as applied to a precipitator of the horizontal flow type, but it will be understood that it is also applicable to precipitators in which the gas flows therethrough in a vertical direction. The drawings show a single precipitator unit and as many of such units may be used as are required for treatment of the volume of gas to be treated and such units may be arranged in either series or 40 parallel relation. The precipitator unit comprises a flue or chamber formed with vertical side walls which are constructed of concrete or other suitable material, with roof or top 2, and with a floor 3. The precipitator shown is especially adapted for precipitation of liquid materials, for example, precipitation of oily, waxy, or tarry substances, resulting from the distillation of carbona-

ceous substances such as oil shale, petroleum, or coal and in such cases, the material precipitated from the gases or vapors being of sufficiently fluid nature to enable it to flow under the action of gravity, the floor or bottom of the flue may be inclined as shown in Fig. 2 so as to cause the material to drain 60 to an outlet conduit indicated at 4. Suitable inlet and outlet dampers 5 and 6 may be provided for controlling the flow of gas through the precipitator and for securing uniformity of distribution of the gas. 65

The top 2 of the treater is provided with openings 7 over which extend removable closure means 8 formed as covers or lids which have down-turned flanges 9 extending into troughs 10 which may contain a sealing liquid or finely divided solid material adapted to seal the joint between these parts, but to permit easy removal of the covers for inspection and repair of the electrodes hereinafter described, the openings 7 and the covers therefor being of sufficient dimensions to enable withdrawal and insertion of the electrode body through the openings when the covers are removed. This mounting of the covers is also a safeguard in case of an explosion when working with combustible gases such as above referred to for the reason that in case of explosion, the covers are lifted by the expansion of the gas within the treater and allow the escape of such gas 85 in such a manner as to avoid undue explosive pressure in the treater chamber.

Collecting electrodes are provided extending longitudinally in the precipitator chamber, said collecting electrodes consisting for example of vertical plates or sheets 12 of metal or conducting material which are provided at their upper ends with top bars 13 adapted to rest on lugs 14 extending from beams 15 which are attached to and form a part of the support for the roof or top of the precipitator. Each collecting electrode may be provided with two top bars formed as angle irons whose horizontal flanges extend outwardly in opposite direction and rest on two opposing lugs 14 and are spaced apart sufficiently to enable the collecting electrodes to be slipped down between them. The lower end of each collecting electrode 100 extends between two angle irons 16 which are mounted on cross bars 17 so as to hold 105

the collecting electrodes in spaced position while permitting expansion and contraction and also permitting the electrodes to be withdrawn vertically upward.

- 5 The discharge electrode system is mounted on insulators 18 enclosed in suitable insulator boxes 19 and supporting cross beams 20 from which hang suspension bars 21 which are provided with upper and lower brackets 10 22 and 23 for supporting and spacing discharge electrodes. Upper bracket 22 is provided with a beam formed as an angle iron 24 extending transversely of the precipitator, and being adapted to support the discharge electrodes. Each discharge electrode comprises a frame formed with horizontal bars 27 and vertical side bars 28 rigidly secured together and discharge electrode members 25 formed as wires, rods, or chains or other conducting elements which are secured to said frame so as to extend across the same in either horizontal direction as shown or in vertical direction as may be desired. In the 15 drawing these discharge electrode elements 20 are shown as fine wires which are secured to the side bars 28 of the discharge electrode frame. Each discharge electrode frame is further provided with a lug 30 extending outwardly from each side bar 28 thereof and 25 adapted to rest on the supporting beam 24 aforesaid. The discharge electrodes are spaced apart at their upper ends by engagement of said lugs in notches 31 in a plate 32, 30 see Figs. 4 and 5, secured to the plate 24, and at their lower ends by lugs 33 on the side bars 28 engaging in notches 34 in a plate 35 which is secured to the lower bracket 23 aforesaid and extends across the precipitator flue. Connection is made from 35 the discharge electrodes system by wire 37 to a switch 38, said switch being in connection by wire 39 with any suitable source of high potential unidirectional electric current supplied, for example, from the secondary 40 of a step-up transformer through a mechanical rectifying device according to the usual practice in the art of electrical precipitation. The collecting electrodes are grounded as indicated at 40.
- 50 In the operation of the apparatus, the gas to be treated, for example, gases and vapors resulting from the distillation of oil shale petroleum, or other carbonaceous material, are passed through the precipitator flue in a horizontal direction, the passage of such gas and vapor being controlled by operation of the dampers 5 and 6. By means of the electric connections aforesaid a high potential difference is maintained between 55 discharge and collecting electrode members with the result that a silent electric discharge is produced from the discharge electrodes and an electro-static field of high potential difference is maintained between the 60 discharge and collecting electrodes. By the 65

operation of such electric discharge and electro-static field the suspended materials in the gases, for example, particles of tar, or oil or other liquid which are suspended in and carried by the gas and vapors are 70 caused to be precipitated upon the electrodes, mainly on the collecting electrodes. A considerable portion of the material so precipitated is in most cases sufficiently liquid to flow down the electrodes under the action of 75 gravity and drains off to the outlet conduit 4. In the operation of the apparatus however there is generally a tendency for material of the nature of paraffine, wax, tar or heavy hydrocarbons to collect on the surface of both the discharge and collecting electrodes and when any considerable amount of the material has so collected it is liable to interfere with the efficiency of the precipitating operation. When this occurs the covers 8 at the top of the precipitator flue may be raised, the dampers 5 and 6 being closed at this time to shut off the supply of gas and vapors and the collecting electrodes and the discharge electrodes can be 80 raised bodily off their supports and up through the openings in the top of the precipitator flue, and after cleaning can be replaced in a similar manner and the cover 85 again put in place. As both the discharge and collecting electrodes rest freely on their supports they may be raised and removed in the manner above described without necessity of loosening any fastening means, and 90 may be reset into position for operation with a minimum of labor and loss of time. In order to permit removal of the discharge electrodes the upper lugs 30 may project somewhat further than the lower lugs 33 and the upper supports 24 and spacing 95 means 32 may be placed at a sufficient distance from the edge of the discharge electrode frame to permit lugs 33 to clear said supports, as shown in Fig. 5. It is possible, 100 however, to make the upper and lower lugs 30 and 33 of the same size, in which case it is only necessary to turn or twist the discharge electrodes horizontally in removing the same so as to permit lug 33 to clear the 105 upper supporting and spacing means. 110

What I claim is:

1. In an electrical precipitator a gas receiving chamber, supports mounted in said chamber, electrodes mounted on said supports to rest freely thereon, said precipitator chamber being provided with an opening in its top through which said electrodes may be removed bodily, said electrodes being mounted for free withdrawal from said supports upwardly through said opening and removable closure means for said opening. 115
2. In an electrical precipitator a gas receiving chamber, grounded supports mounted in said chamber, collecting electrodes mounted on said supports to rest freely 120

thereon, said precipitator chamber being provided with an opening in its top through which said collecting electrodes may be removed bodily, said electrodes being mounted for free withdrawal from said supports upwardly through said opening and removable closure means for said opening.

3. In an electrical precipitator a gas receiving chamber insulated supports mounted in said chamber, discharge electrodes mounted on said supports to rest freely thereon, said precipitator chamber being provided with an opening in its top through which said discharge electrodes may be removed bodily, said electrodes being mounted for free withdrawal from said supports upwardly through said opening and removable closure means for said opening.

4. In an electrical precipitator a gas receiving chamber, grounded and insulated supports mounted in said chamber, collecting and discharge electrodes mounted on said respectively grounded and insulated supports to rest freely thereon, said precipitator chamber being provided with an opening in its top through which said collecting and discharge electrodes may be removed bodily, said electrodes being mounted for free withdrawal from said supports upwardly through said opening and a removable closure means for said opening.

5. An electrical precipitator comprising a gas receiving chamber, grounded collecting electrode supports mounted in said chamber, insulated discharge electrode supports mounted in said chamber, collecting electrodes resting freely on said collecting electrode supports and adapted to be raised bodily therefrom, discharge electrodes resting freely on said discharge electrode supports and adapted to be lifted bodily therefrom, said gas receiving chamber being provided with openings at its top through which the discharge and collecting electrodes may be removed, said collecting and discharge electrodes being

mounted for free and unobstructed movement independently of one another upwardly from said supports and through said opening and removable closure means for said openings.

6. A construction as set forth in claim 5, and comprising in addition spacing means in connection with the collecting electrode supports for spacing apart the collecting electrodes and spacing means in connection with the discharge electrodes for spacing the discharge electrodes, the respective electrodes being in loose engagement with said spacing means so as to permit said electrodes to be removed upwardly from their respective supports and spacing means.

7. In an electrical precipitator, a gas receiving chamber, supports mounted in said chamber, collecting and discharge electrodes mounted on said supports resting freely thereon, said precipitator chamber being provided with an opening in its top in which said collecting and discharge electrodes may be removed bodily, and a removable closure means for said opening resting freely on the top of the said chamber so as to permit automatic opening thereof for operation as a relief valve in case of an explosion within said chamber.

8. A construction as set forth in claim 7 and comprising in addition seal means on top of said chamber for closing the joint between said closure means and the top of the chamber while permitting free upward movement of said closure means.

9. A construction as set forth in claim 7 and comprising in addition troughs on the top of said chamber, said closure means having down-turned flanges extending into said troughs, and sealing material within said troughs sealing the joint between said flanges and the trough.

In testimony whereof I have hereunto subscribed my name this 24th day of July 1923.

CHARLES H. WEISKOPF.
